18 Claims. (Cl. 178—44)

1

This invention relates, in general, to wave-signal translating arrangements, especially those adapted to translate pulse-modulated signals. While being subject to a variety of applications, the invention is particularly suited for use in a radio-locating and direction-finding system of the type utilizing pulse-modulated signals and will be described in that connection.

At the outset, consider a locating and direction-finding system in which the desired information is conveyed by means of a pulse-modulated signal, coded in accordance with a prescribed coding schedule. For example, the coded signal may include a pair of pulse components, individually having a rectangular wave form and fixed duration but a time separation that is variable in a code sequence. In the preferred systems, the coded signal is received, shaped and passed on to a decoder unit which automatically derives the desired information by deciphering the coded signal.

Systems of the type mentioned above operate satisfactorily in electrically quiet installations that are substantially free of interfering signals. Where there is a strong likelihood of encountering noise or interfering signals of appreciable magnitude, however, the decoder is liable to produce erroneous information. Assume for the purposes of illustration that a noise or interfering pulse component is present having an amplitude half that of the pulse components of the received coded signal referred to. Further, assume the interfering pulse to occur intermediate the coded pulse components of the received signal. Under the assumed conditions, the decoder may be unable to distinguish between the desired code components and the spurious or interfering signal component appearing in the output circuits of the preceding stages. When such is the case, the spurious signal is accepted as a component of the received coded signal and the deciphered information derived from the decoder is obviously faulty and misleading.

Quick acting automatic-volume-control arrangements are known in the art which may respond to the leading component of a received signal and reduce the receiver gain to such an extent that an interfering signal of the type under consideration is not translated therethrough and does not appear in the receiver output circuit. Such control arrangements usually comprise a detector and an associated condenser having a fast charging time constant but a slow discharging time constant. Where this arrangement is used, the condenser is charged in response

2

to the leading component of the received signal and establishes a control potential for reducing the receiver gain as required to eliminate the interfering signal mentioned above. The long discharge time constant of the condenser enables the control voltage to hold over and maintain reduced gain in the receiver for the duration of the received signal. After the duration of the received signal, the control voltage is gradually decreased, as the condenser discharges, and normal receiver gain and sensitivity are gradually restored. Such arrangements are operative but the slow process of re-establishing the receiver gain after the termination of a received signal may be undesirable for recurring sets of pulses.

It is an object of the present invention, therefore, to provide a wave-signal translating arrangement for translating modulated signals and which substantially avoids the aforementioned limitations of prior arrangements.

It is another object of the present invention to provide an improved arrangement for translating a modulated signal having a predetermined maximum duration and including a control system for effecting a desired variation in an operating characteristic of the arrangement but only during an operating interval approximately corresponding to the duration of the modulated signal.

It is a specific object of the invention to provide an improved arrangement for translating a modulated signal having a predetermined maximum duration and including a gain-control system for substantially reducing the gain level of the arrangement but only for the duration of the modulated signal.

In accordance with the invention, a wave-signal translating arrangement for translating a modulated signal which may have a predetermined maximum duration comprises a signal-translating channel. The channel has a predetermined operating characteristic which has a normal value in the absence of the modulated signal. The arrangement includes means responsive to the modulated signal for deriving a control potential starting early in the duration of the modulated signal and tending to hold over for an interval substantially greater than the aforesaid maximum duration. There are provided means for utilizing the control potential to adjust the operating characteristic of the channel to a value different from its normal value. Additionally, the arrangement has means for effectively interrupting the control potential and for restoring the operating characteristic of the channel to its normal value after a predetermined time in-

terval at least approximately equal to the aforesaid maximum duration.

For a better understanding of the present invention, together with other and further objects thereof, reference is had to the following description taken in connection with the accompanying drawings, and its scope will be pointed out in the appended claims.

In the drawings, Fig. 1 is a schematic representation of a wave-signal translating arrangement in accordance with the invention; Fig. 2 comprises graphs utilized in explaining the operation of the Fig. 1 arrangement; Fig. 3 represents a further wave-signal translating arrangement including the invention in modified form; and Fig. 4 comprises a series of graphs used in explaining the operation of the Fig. 3 arrangement.

Referring now more particularly to Fig. 1, the wave-signal translating arrangement there represented may be considered as the receiving unit of a radio-locating and direction-finding system. The system is constructed to utilize pulse-modulated signals which have a predetermined minimum peak value and which may have a predetermined maximum duration. The nature of the pulse-modulated signal is to be considered more particularly in connection with the operation of the illustrated arrangement. This arrangement comprises an antenna-ground system 10, 11 for intercepting the pulse-modulated direction-finding signals and for applying such signals to a signal-translating channel provided by a pulse-modulated signal receiver 12, a wave-signal limiter 13 and an oscilloscope 14 connected in cascade in the recited order. The receiver unit 12 may constitute any conventional well-known arrangement for receiving and demodulating pulse-modulated signals. As is well understood in the art, receivers both of the superheterodyne and superregenerative types may be utilized for this purpose. In the instant case, unit 12 will be deemed to be of the superregenerative type and will be understood to include an oscillator for supplying a quench voltage. Limiter 13 may be a conventional amplifying arrangement in which pulse-modulated signals are shaped by clipping and amplitude-limiting actions. This may be accomplished by operating the stage to translate only an intermediate amplitude range of an applied pulse eliminating its maximum and minimum levels by way of anode current saturation and anode current cutoff phenomenon, respectively. The oscilloscope 14 may be of the familiar cathode-ray type used to monitor the wave-signal translating arrangement under consideration. The pulse-modulated signals obtained in the output circuit of limiter 13 may be applied to an automatic decoding unit (not shown), as indicated by arrow 19.

In view of the high amplification obtainable with receiver 12, a quiescent signal of appreciable magnitude is translated in channel 12-14, inclusive, during operating intervals in which modulated signals are not intercepted by antenna system 10, 11. This quiescent signal is initiated by and represents inherent disturbances within the receiver as, for example, thermal agitation noise, shot effect and the like. Also, this signal may be utilized to control a desired operating characteristic of the signal-translating channel, such as its gain or other similar operating characteristic. For purposes of illustration, it will be assumed that the channel gain is to be controlled.

The amplitude of the quiescent signal output

reflects the value of the receiver gain. A first or noise gain-control system 15 is associated with the channel and constitutes means responsive to the quiescent signal translated therethrough for stabilizing the gain characteristic of the channel at a desired normal value. Unit 15 may include a frequency-selective amplifying circuit and a wave-signal rectifier for rectifying a selected portion of the quiescent signal output to derive in the output circuit of unit 15 a control potential having an amplitude determined by that of the quiescent signal. A time constant circuit, comprising the parallel combination of a condenser 16 and a resistor 17, is included in the output circuit of unit 15. The values of elements 16 and 17 are selected to provide a long time constant so that the control potential obtained from unit 15 is not appreciably disturbed by received signal pulses of short duration occurring infrequently and translated in the signal-translating channel. The connection 18 extending from time constant circuit 16, 17 through receiver 12 applies the gain-control potential from unit 15 to a control circuit or bias arrangement of the receiver to effect the desired gain-stabilization phenomenon. A suitable circuit arrangement for receiver 12 and its associated noise gain-control system 15 is fully disclosed in copending application Serial No. 521,932, filed February 11, 1944, in the name of Harold A. Wheeler and assigned to the same assignee as the present invention.

The signal-translating arrangement has means exclusive of channel 12-14 and responsive to a received pulse-modulated signal for deriving a second control potential starting early in the duration of the received signal and tending to hold over for an interval substantially greater than the maximum duration of the received signal. This means is designated 20 and is said to be exclusive of the principal translating channel because wave-signal translation from the antenna 10, 11 to the decoder is accomplished independently of this unit. Unit 20 includes means, a pulse rectifier and amplifier 21, which respond to the leading portion of the pulse-modulated signal for deriving a signal pulse of a given polarity. The pulse rectifier of unit 21 is preferably a peak rectifier so that the signal pulse obtained therefrom has a magnitude determined by the peak value of the pulse-modulated signal applied to its input circuit from receiver 12 by way of connection 32. Also, the rectifier of unit 21 preferably has an amplitude-delay bias so as to be amplitude selective. The value of bias is selected so that the rectifier is unresponsive to signals having an intensity less than the minimum peak value of pulse-modulated signals to be received.

The output circuit of the amplifying portion of unit 21 is coupled through a pair of amplifying or repeating vacuum tubes 22 and 23 of the tetrode type to an energy-storage device 24 which is to be charged in one sense by the signal pulse from unit 21 to develop a control potential. The input circuit of tube 22 is connected to unit 21 through a condenser 26 and a grid resistor 27. In similar manner, a condenser 28 and grid resistor 29 couple the output circuit of tube 22 to the input circuit of tube 23. Operating potentials are applied to these tubes from the sources indicated +B, +S, and -E. A resistor 25 is shunted across the energy-storage device or condenser 24, having such value that the discharge path of condenser 24 has a very slow time constant much greater than the maximum duration of the received pulse-modulated signals. A connection 30 extending

from the time constant circuit 24, 25 to the gain-control input circuit of receiver 12 provides means for utilizing the control potential to adjust the gain characteristic of the receiver to a value different from its normal value.

In order that the receiver may have its different or abnormal gain level for only a selected operating interval, the arrangement further includes means for effectively interrupting the control potential from unit 20 and for restoring the gain characteristic of the receiver to its normal value. This means comprises a short-circuited time-delay network 31 having a conventional construction and including series-connected inductors and intervening shunt-connected condensers. The input terminals of network 31 are coupled across a load impedance 35 included in the output circuit of amplifier 22. The impedance 35 is selected to terminate the network in its characteristic impedance.

While a transmitting unit is customarily associated with a receiving unit of the type represented in Fig. 1 to complete the radio-locating and direction-finding system, the present invention may be clearly understood from a consideration of only the receiver portion. For this reason the remainder of the direction-finding system has been omitted from the drawings. The operation of the Fig. 1 arrangement is represented in part by the curves of Fig. 2.

Curve A designates the signal output obtained from receiver 12 of the signal-translating channel 12-14, inclusive. The low-amplitude signal portions designated S_q denote the stabilized quiescent signal output of the receiver, stabilized by control unit 15 in the manner fully disclosed in the above-identified copending application. The pulse components P_1 , P_2 and P_3 constitute a received direction-finding signal of the pulse-modulated type which has a duration T_1 but which may have a maximum duration T_0 . The leading pulse component P_1 is a pilot pulse and the succeeding components P_2 and P_3 have a time spacing which is coded in accordance with a prescribed coding schedule. Each component has a peak amplitude value exceeding a minimum peak amplitude level represented by broken horizontal line B. The pulse component P_4 represents an interfering pulse component, such as an echo, which is received along with the pulse-modulated signal in the interval between its components P_1 and P_2 . The undesired signal P_4 has an appreciable amplitude in comparison with that of the code components. Therefore if the signal of curve A were supplied directly to the decoder, the interfering pulse component P_4 would cause an error in the deciphering operation. This undesired result is obviated by the pulse gain-control unit 20 of the Fig. 1 arrangement in the following manner.

The signal of curve A is applied directly to the input circuit of pulse rectifier and amplifier 21. The amplitude-delay bias of this unit has a value which may also be represented by broken-line curve B. It has a value established at a level exceeding the stabilized amplitude level of the quiescent signal output S_q of receiver 12. Consequently, the noise gain-control system 15 prevents the quiescent signal S_q of channel 12-14, inclusive, from initiating the additional control afforded by unit 20.

At the time t_0 , the pilot-pulse component P_1 of the received pulse-modulated signal arrives at the input terminals of unit 21 included in the pulse gain-control system 20. As the amplitude

of the applied pulse exceeds the amplitude-delay bias of the rectifier in unit 21, this pulse is peak rectified and translated through tube 22. In the output circuit of tube 22, part of the signal energy is applied to time-delay network 31, the remainder being applied directly to the input circuit of tube 23 as a pulse signal of positive polarity. This pulse signal is represented at P_5 in curve C. The pulse signal P_5 is further amplified in tube 23, reversed in polarity and applied to condenser 24, charging the condenser in one sense to develop the control potential of curve D. The control potential is negative and attains its maximum value, indicated e_1 , after the short time interval $t_0 - t_1$. The interval $t_0 - t_1$ is short compared with the duration $t_0 - t_2$ of the pilot-pulse component P_1 and, thus, the pulse gain-control system is seen to be fast acting. It develops the desired control potential of curve D early in the duration of the pulse-modulated signal of curve A.

The developed control potential is utilized as a bias or gain-control potential, being supplied to the control input circuit of receiver 12 to reduce the gain thereof and the gain of channel 12-14, inclusive, from the normal value established by the noise gain-control system 15. Preferably, the gain of the signal-translating channel is reduced to decrease the amplitude of the pulse-modulated signal of curve A in the manner illustrated by curve E. Specifically, the gain is quickly reduced so that only the leading portion of the pilot-pulse component P_1 exceeds the amplitude-delay bias of the rectifier of unit 21. This reduction in gain determines the wave form of signal pulse P_5 of curve C which is consequently of shorter duration than the pilot-pulse component P_1 . In view of the slow discharge time constant of condenser 24 and resistor 25, the control potential of curve D tends to hold up substantially at its peak value e_1 for a time interval much longer than the maximum pulse duration T_0 . Therefore, the received pulse-modulated signal of curve A is translated to the input circuits of limiter 13 and unit 21 with the wave form of curve E.

The limiter 13 is adjusted, in conventional manner, to clip applied signal components at clipping levels designated by the horizontal broken lines F and G. The clipping process removes the irregular noise components that are superimposed on the pulse components P_1 , P_2 and P_3 of the received coded signal. This process also eliminates signal components of amplitudes less than clipping level G and deletes the residual portion of the undesired noise pulse component P_4 , obtaining the output signal of curve H. This signal, in turn, is supplied to the oscilloscope 14 where the performance of channel 12-14, inclusive, may be determined by reproducing the wave form of curve H on the screen of a cathode-ray tube in well-known fashion. The output signal of the limiter is also supplied to the automatic decoder (not shown) wherein the coded information conveyed by means of the time separation of pulse components P_2 and P_3 is deciphered.

At the time t_5 , a reflection of signal P_5 of curve C appears at the input terminals of time-delay network 31. The reflected pulse, P_6 of curve C, has a time separation $t_0 - t_5$ from pulse P_5 which corresponds with the total or round-trip delay of the network. This delay is proportional to the geometric mean of the total series inductance and total shunt capacitance of network 31 and is preselected to cause the interval $t_0 - t_5$ to be

only slightly greater than the maximum duration T_0 of the coded signals to be received in the operation of the system. The reflected pulse P_6 is of negative polarity, receiving a polarity reversal at the short-circuited termination of the network 31. The delayed and reversed polarity signal pulse P_6 is translated through tube 23 to condenser 24. This pulse charges the condenser in an opposite sense to the charging effect of the direct pulse P_5 or, expressed differently, discharges condenser 24 to interrupt or terminate the control potential of curve D. With the control potential of curve D terminated, the noise gain-control system 15 resumes control and restores the gain of channel 12-14, inclusive, to its normal or stabilized value.

By way of review, the arrangement of Fig. 1 will be seen to include two gain-control systems. The first, noise gain-control system 15, establishes a desired normal or stabilized gain in channel 12-14, inclusive. The second, pulse gain-control system 20, is ineffective in the absence of a received signal. Upon receipt of a signal, however, unit 20 responds rapidly to develop a control potential for materially reducing the channel gain early in the duration of the received signal. The amplitude-delay bias feature of unit 20 renders this unit responsive to only the leading portion of the received signal. The discharge time constant of condenser 24 and resistor 25 is preferably several times the total delay of network 31 so that the condition of reduced gain tends to endure for an operating interval much greater than the maximum duration of the received signals. The delay of network 31 is selected so that this reduced gain condition is terminated and normal gain restored to the channel after an interval only slightly longer than the maximum duration of the received signals. Consequently, while the channel has a reduced gain for about the duration of the received pulse-modulated signal in order to minimize the effects of spurious pulse components of the type shown at P_4 , the normal high gain is re-established just after the received pulse has been translated. In this manner, the arrangement is returned to a condition of high sensitivity promptly to be certain to translate the next succeeding pulse-modulated signal even though it be of reduced intensity.

A modification of the invention is included in the representation of Fig. 3 showing a signal-translating arrangement embodying a receiver of the superheterodyne type. The arrangement has an antenna-ground system 40, 41 for supplying received signals to a receiving unit. The receiver comprises a radio-frequency amplifier 42 of one or more stages and an oscillator-modulator or frequency converter 43. At the output circuit of oscillator-modulator 43, the arrangement branches into two signal-translating channels. One such channel, the gain-control channel, includes an intermediate-frequency amplifier 44 of one or more stages directly coupled to oscillator-modulator 43. Amplifier 44 applies signals to a noise gain-control system 45 and to a pulse gain-control system 46. Units 45 and 46 may be the same as units 15 and 20, respectively, of Fig. 1. A control potential obtained in unit 45 is applied over a conductor 47 to units 42, 43 and 44 to stabilize the gain of the first channel at a desired normal value. A control potential obtained from unit 46 is applied over a conductor 48 to intermediate-frequency amplifier 44 to shift the gain level of the first channel

from its normal value to a different value for operating intervals during which received signals are being translated.

The other, or second, channel is coupled to oscillator-modulator 43 through a time-delay network 50. This channel has an intermediate-frequency amplifier 51 of one or more stages, a wave-signal detector and amplifier 52, a limiter 53 and an oscilloscope 54. The output signal of limiter 53 may also be supplied to an automatic decoder, as indicated by arrow 55. Input terminals of intermediate-frequency amplifier 51 receive connections from conductors 47 and 48, extending the control of systems 45 and 46 to the gain characteristic of the second channel.

The operation of the Fig. 3 arrangement will be understood from the foregoing description and the curves of Fig. 4 which are generally similar to the curves of Fig. 2, corresponding parts thereof being identified by the same reference characters primed. In the absence of a received pulse-modulated signal, unit 45 utilizes the quiescent signal of the receiver to stabilize the gain, or other controlled operating characteristic, of the first and second channels of the Fig. 3 arrangement at a desired normal value. This control is superseded by the effect of unit 46 in the presence of a received signal, such as that of curve A'.

The signal of curve A' differs principally from that of curve A in that it represents one-half of the envelope of the signal output of oscillator-modulator 43 and that it contains no pilot-pulse component. Such a component is not required to achieve the desired control in a system of the type of Fig. 3. The pulse components P_2' and P_3' are similar to components P_2 and P_3 of Fig. 2, having a time separation in accordance with a prescribed coding schedule. At the time t_0' , pulse component P_2' is applied to unit 46 which derives the control potential of curve D' in the manner recited above.

The control potential of curve D' obtains its maximum value e_1' at the time t_1' . This control potential as applied to intermediate-frequency amplifiers 44 and 51 reduces the gain level in both the first and second signal-translating channels to suppress interfering signals of the type represented by pulse component P_4' . The time-delay network 50 through which the output signal of oscillator-modulator 43 is applied to the second channel is selected to have a time delay $t_0' - t_6'$. The delay interval $t_0' - t_6'$ is selected to be slightly longer than the time $t_0' - t_1'$ required for the gain level of the second channel to be reduced under the control of unit 46. As a consequence, the output signal of detector and amplifier 52 has the wave form of curve E'. It is clipped in unit 53 and supplied to both oscilloscope 54 and the automatic decoder (not shown) with the wave form of curve H'.

Inasmuch as the received coded signal is applied to intermediate-frequency amplifier 51 with a time delay, the pulse gain-control system 46 is adjusted so that the control potential of curve D' is terminated to restore the normal gain level in the first and second channels only after the second channel has experienced the reduced gain for an interval approximately equal to or slightly greater than the maximum duration T_0' of the received signals.

The time-delay network 50 for delaying the application of the pulse-modulated signal to amplifier 51 until the control potential of curve D' has been developed preserves the wave form

of the received signal. Otherwise, the leading and trailing edges of pulse P_2' of the received signal are limited to different degrees in the manner of the pilot pulse P_1 in the series of curves of Fig. 2.

From the foregoing description, certain salient features of the present invention become apparent. In the first place, with a fast-acting pulse gain-control system the receiver may have high gain and high sensitivity in the absence of received signals which is desirable in that it permits even weak signals to be translated. While this high sensitivity renders the receiving arrangement subject to interfering signals, such as reflected echoes or unusually large noise signals, the fast-acting pulse gain-control system minimizes the effect of such undesired signals on the receiver. The limiter stages suppress any residuum of such interfering signal components from the coded signal applied to the decoder.

Another especially desirable feature of the arrangement is its ability to protect the units thereof as well as the decoder from the effects of a nearby transmitting unit operating at approximately the same frequency. In such installations, the pulse gain-control system is able to derive a control potential in response to the leading portion of a transmitted signal intercepted by its antenna system and to reduce the gain of the arrangement to such an extent that the transmitted signal is not able to cause overloading and other undesired results.

The invention may be utilized for translating modulating signals of a variety of wave forms. The term "modulated signal" as used herein and in the appended claims is intended to mean a signal having a large amplitude level for a selected time interval followed by a low-amplitude portion of substantial duration.

The control potential derived in the pulse gain-control systems of Figs. 1 and 3 is applied to tubes of the gradual cutoff type, which preserves the wave shape of the signals translated in the associated signal-translating channels. However, if desired, the controlled tubes may have sharp cutoff characteristics. In such a case, the control potential from the pulse gain-control system may cause all signals below a certain level of the incoming signal, say 50 percent, to be eliminated directly. Where the controlled tubes are of this type, limiter 13 need only clip the upper portion of its input signal to remove the noise components superimposed on the pulse components of the received signal.

For convenience of illustration, idealized wave forms are shown in Figs. 2 and 4. In practical operation the pulse components of the received coded signal are trapezoidal instead of rectangular in form. Limiting or clipping of such pulse components may tend to cause the limited signal to have pulse widths that vary with the strength of the received signal. An arrangement for obviating this pulse width variation is fully disclosed in copending application Serial No. 597,037, filed June 1, 1945, and assigned to the same assignee as the present invention.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A wave-signal translating arrangement for translating a modulated signal which may have a predetermined maximum duration comprising, a signal-translating channel having a predetermined operating characteristic which has a normal value in the absence of said modulated signal, means responsive to said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.
2. A wave-signal translating arrangement for translating a modulated signal which may have a predetermined maximum duration comprising, a signal-translating channel having a predetermined operating characteristic which has a normal value in the absence of said modulated signal, means responsive to said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval greater than said maximum duration.
3. A wave-signal translating arrangement for translating a modulated signal which may have a predetermined maximum duration comprising, a signal-translating channel having a predetermined operating characteristic which has a normal value in the absence of said modulated signal, means responsive to said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval only slightly greater than said maximum duration.
4. A wave-signal translating arrangement for translating a modulated signal which may have a predetermined maximum duration comprising, a signal-translating channel having a predetermined operating characteristic which has a normal value in the absence of said modulated signal, means responsive to said modulated signal for deriving a control potential starting early in the duration of said signal, tending to hold over for an interval substantially greater than said maximum duration and having a magnitude determined by the intensity of said modulated signal, means for utilizing said control potential to adjust said operating characteristic from its normal value to a different value determined by the magnitude of said control potential, and means for effectively interrupting said control potential and for restoring said operating characteristic to its normal value after a predetermined time in-

terval at least approximately equal to said maximum duration.

5. A wave-signal translating arrangement for translating a modulated signal which may have a predetermined maximum duration comprising, a signal-translating channel having a predetermined operating characteristic which has a normal value in the absence of said modulated signal, rectifier means responsive to said modulated signal for deriving a control potential starting early in the duration of said signal, tending to hold over for an interval substantially greater than said maximum duration and having a magnitude determined by the value of said modulated signal, means for utilizing said control potential to adjust said operating characteristic from its normal value to a different value determined by the magnitude of said control potential, and means for effectively interrupting said control potential and for restoring said operating characteristic to its normal value after a predetermined time interval at least approximately equal to said maximum duration.

6. A wave-signal translating arrangement for translating a modulated signal which may have a predetermined maximum duration comprising, a signal-translating channel having a predetermined operating characteristic which has a normal value in the absence of said modulated signal, means exclusive of said channel and responsive to said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.

7. A wave-signal translating arrangement for translating a modulated signal which may have a predetermined maximum duration comprising, a signal-translating channel having a predetermined operating characteristic which has a normal value in the absence of said modulated signal, means responsive to the leading portion of said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.

8. A wave-signal translating arrangement for translating a modulated signal which may have a predetermined maximum duration comprising, a signal-translating channel having a predetermined operating characteristic which has a normal value in the absence of said modulated signal, means including an energy-storage device to be charged in response to said modulated signal for deriving a control potential starting early in the duration of said signal and tending to hold over for an interval substantially greater than said maximum duration, means for utilizing said control potential to adjust said operating characteristic to a value different from said normal value, and means for discharging said energy-

storage device to interrupt said control potential and restore said operating characteristic to its normal value after a predetermined time interval at least approximately equal to said maximum duration.

9. A wave-signal translating arrangement for translating a modulated signal which may have a predetermined maximum duration comprising, a signal-translating channel having a predetermined operating characteristic which has a normal value in the absence of said modulated signal, means responsive to the leading portion of said modulated signal for deriving a signal pulse, means including an energy-storage device to be charged by said signal pulse for developing a control potential starting early in the duration of said signal and tending to hold over for an interval substantially greater than said maximum duration, means for utilizing said control potential to adjust said operating characteristic to a value different from said normal value, and means for discharging said energy-storage device to interrupt said control potential and restore said operating characteristic to its normal value after a predetermined time interval at least approximately equal to said maximum duration.

10. A wave-signal translating arrangement for translating a modulated signal which may have a predetermined maximum duration comprising, a signal-translating channel having a predetermined operating characteristic which has a normal value in the absence of said modulated signal, means responsive to the leading portion of said modulated signal for deriving a signal pulse of a given polarity, means including an energy-storage device to be charged by said signal pulse for developing a control potential starting early in the duration of said signal and tending to hold over for an interval substantially greater than said maximum duration, means for utilizing said control potential to adjust said operating characteristic to a value different from said normal value, and time-delay means for applying said signal pulse to said energy-storage device with reversed polarity to discharge said energy-storage device to interrupt said control potential and restore said operating characteristic to its normal value after a predetermined time interval at least approximately equal to said maximum duration.

11. A wave-signal translating arrangement for translating a modulated signal which may have a predetermined maximum duration comprising, a signal-translating channel having a predetermined operating characteristic which has a normal value in the absence of said modulated signal, means responsive to the leading portion of said modulated signal for deriving a signal pulse of a given polarity, means including an energy-storage device to be charged by said signal pulse for developing a control potential starting early in the duration of said signal and tending to hold over for an interval substantially greater than said maximum duration, means for utilizing said control potential to adjust said operating characteristic to a value different from said normal value, and means including a short-circuited time-delay network for applying said signal pulse to said energy-storage device with reversed polarity to discharge said energy-storage device to interrupt said control potential and restore said operating characteristic to its normal value after a predetermined time interval at least approximately equal to said maximum duration.

12. A wave-signal translating arrangement for translating a modulated signal which may have

a predetermined maximum duration comprising, a signal-translating channel having a predetermined gain characteristic which has a normal value in the absence of said modulated signal, means responsive to said modulated signal for deriving a control potential starting early in the duration of said signal and tending to hold over for an interval substantially greater than said maximum duration, means for utilizing said control potential to adjust said gain characteristic to a value different from said normal value, and means for effectively interrupting said control potential and for restoring said gain characteristic to its normal value after a predetermined time interval at least approximately equal to said maximum duration.

13. A wave-signal translating arrangement for translating a modulated signal having a predetermined minimum peak value and a duration which may have a predetermined maximum value comprising, a signal-translating channel having a predetermined gain characteristic which has a normal value in the absence of said modulated signal, amplitude-selective means coupled to said channel and unresponsive to signals having an intensity less than said predetermined peak value for deriving a signal pulse of a given polarity from the leading portion of said modulated signal, means including an energy-storage device to be charged by said signal pulse for developing a control potential starting early in the duration of said signal and tending to hold over for an interval substantially greater than said maximum duration, means for utilizing said control potential to reduce the value of said gain characteristic so that the peak value of said modulated signal as applied to said amplitude-selective means is decreased early in the duration thereof to a value less than said predetermined peak value, and a time-delay means for applying said signal pulse to said energy-storage device with reversed polarity to discharge said energy-storage device to interrupt said control potential and restore said gain characteristic to its normal value after a predetermined time interval at least approximately equal to said maximum duration.

14. A wave-signal translating arrangement for translating a modulated signal which may have a predetermined maximum duration comprising, a signal-translating channel having a predetermined operating characteristic and effective in the absence of said modulated signal to translate a quiescent signal representing inherent disturbances within said translating arrangement, means responsive to said quiescent signal for stabilizing said operating characteristic at a desired normal value, means responsive to said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.

15. A wave-signal translating arrangement for translating a modulated signal which may have a predetermined maximum duration and which includes a leading pilot-pulse component comprising, a signal-translating channel having a predetermined operating characteristic which has

a normal value in the absence of said modulated signal, means responsive to said pilot-pulse component of said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.

16. A wave-signal translating arrangement for translating a modulated signal which may have a predetermined maximum duration and which includes a leading pilot-pulse component comprising, a signal-translating channel having a predetermined operating characteristic which has a normal value in the absence of said modulated signal, means responsive substantially only to said pilot-pulse component of said modulated signal for deriving a control potential starting early in the duration of said signal and tending to hold over for an interval substantially greater than said maximum duration, means for utilizing said control potential to adjust said operating characteristic to a value different from said normal value, and means for effectively interrupting said control potential and for restoring said operating characteristic to its normal value after a predetermined time interval at least approximately equal to said maximum duration.

17. A wave-signal translating arrangement for translating a modulated signal which may have a predetermined maximum duration comprising, a first signal-translating channel including means responsive to said modulated signal for deriving a control potential starting early in the duration of said signal and tending to hold over for an interval substantially greater than said maximum duration, a second signal-translating channel having a predetermined operating characteristic which has a normal value in the absence of said modulated signal, means for utilizing said control potential to adjust said operating characteristic of said second channel to a value different from said normal value, means for applying said modulated signal directly to said first channel and for applying said modulated signal to said second channel with a time delay at least equal to the delay of said first channel in deriving said control potential, and means for effectively interrupting said control potential and for restoring said operating characteristic of said second channel to its normal value after a predetermined time interval at least approximately equal to said maximum duration.

18. A wave-signal translating arrangement for translating a modulated signal which may have a predetermined maximum duration comprising, a first and a second signal-translating channel each of which has a predetermined operating characteristic having a normal value in the absence of said modulated signal, means included in said first channel and responsive to said modulated signal for deriving a control potential starting early in the duration of said signal and tending to hold over for an interval substantially greater than said maximum duration, means for utilizing said control potential to adjust the operating characteristic of each channel to a value different from said normal value, means for applying said modulated signal directly to said first

channel and for applying said modulated signal to said second channel with a time delay at least equal to the delay of said first channel in deriving said control potential, and means for effectively interrupting said control potential and for restoring said operating characteristic of each channel to its normal value after a predetermined time interval at least equal to said maximum duration.
